TRACTION LUG

Filed July 20, 1928

UNITED STATES PATENT OFFICE

BRUNO ARPS, OF NEW HOLSTEIN, WISCONSIN

TRACTION LUG

Application filed July 20, 1928. Serial No. 294,135.

This invention relates to traction lugs.

Traction lugs, as heretofore constructed, have usually been made of castings. These castings are difficult and may be fairly easily broken by encountering unusual conditions for which they are not designed; for example, when a stump or rock is struck by the traction lug during traction operation.

This invention is designed to provide a novel form of traction lug which is very easy to make, which is formed from sheet metal and requires no castings, which is readily pressed into shape, and which is provided with sheet metal guiding lugs for the wheels which are spot welded to the body of the lug.

Further objects are to provide a traction lug which has an open central portion, which is provided with gripping fins to secure a firm grip upon the ice or snow, and which also is provided with a wedge-shaped web or projection on opposite sides of the central opening so that it will break the ice cake that may form around the central opening, the central opening allowing the free discharge of ice or snow due to the action of the tire.

An embodiment of the invention is shown in the accompanying drawings in which:

Figure 1 is a side elevation of the device with a part in section;

Figure 2 is a view from the underside of the device;

Figure 3 is an end view of the device.

The traction lug or tread piece comprises a sheet metal body portion 1 which is provided with a central aperture 2. The central aperture 2 is punched through the device and a surrounding downwardly projecting flange 3 is pressed from the body portion, as is apparent from an examination of Figures 2 and 3. Further, a portion of the side edges of the body portion is pressed downwardly, as indicated at 4. This downwardly extending portion is formed on opposite sides of the body portion, as shown in Figures 2 and 3, and extends downwardly, preferably to a lesser depth than the web 3.

Further, it is to be noted from Figures 1 and 3 that the body portion has a hollow, downwardly projecting rib 5 pressed there-

from. This rib is interrupted by the central opening and extends from opposite sides of the central opening to the extreme side edges of the device. It is of V or wedge shape and acts to break up any cake of ice that may be formed beneath this portion of the device, so that packing cannot occur.

The body portion carries at opposite ends strap members 6 which are turned or looped, as indicated at 7, to receive the connecting chains 8. The inturned portions 8 are secured together with a portion of the part 6 to the body of the traction lug by means of bolts 9. Preferably, spacers 10 are positioned between the portions 6 and 8 of the strap member. It is to be noted that the portion 7 is also laterally curved to fit the link and to thus provide an extensive bearing surface.

A pair of wheel engaging lugs or inwardly extending projections 11 are also formed from sheet metal and are provided with lateral feet 12 which are spot welded to the body portion. Further, these lugs are each provided at their inner lateral ends with an outwardly extending tongue 13 which fits within the central aperture 2 and is welded to the adjacent portion of the body portion.

It will be seen from Figure 1 that the tongues 13 and the feet 12 securely anchor the wheel engaging members 11. These members present a curved face to the wheel and also guide the wheel downwardly towards the central portion of the device. The central portion of the body is curved or arched downwardly, as may be seen from Figure 1, so as to provide a contacting surface for the wheel which approximately fits the contour of the tire.

It is to be noted that the strap members 6 freely transmit the stresses or tension of the chains from one side of the device to the other.

It will be seen further that the traction lug or tread piece is of very light weight but of great strength, as it is formed of sheet metal pressed to the shape described above and thus equipped with sufficient rigidity to withstand the forces applied thereto.

It will be seen further that the traction lug may be cheaply produced and is of relatively simple construction.

Although the invention has been described in considerable detail, such description is intended as illustrative rather than limiting as the invention may be variously embodied and as the scope of such invention is to be determined as claimed.

15 I claim:

19 A traction shoe including a body having a central opening, inwardly projecting wheel guide lugs having inclined guide faces, lateral feet on each lug secured to the inner face of the body and tongues on the inner lateral ends of said lugs projecting into the central opening and secured to said body.

15 In testimony that I claim the foregoing I have hereunto set my hand at New Holstein, in the county of Calumet and State of Wisconsin.

20 BRUNO ARPS.
